(57) **CLAIM**

We claim the ornamental design for handle for holding a sampling sponge, as shown and described.

DESCRIPTION

FIG. 1.1 is a perspective view of a handle for holding a sampling sponge showing our new design;

FIG. 1.2 is a front view of the handle for holding a sampling sponge of FIG. 1.1;

FIG. 1.3 is a right side view of the handle for holding a sampling sponge of FIG. 1.1;

FIG. 1.4 is a left side view of the handle for holding a sampling sponge of FIG. 1.1;

FIG. 1.5 is a rear view of the handle for holding a sampling sponge of FIG. 1.1;

FIG. 1.6 is a top plan view of the handle for holding a sampling sponge of FIG. 1.1;

FIG. 1.7 is a bottom plan view of the handle for holding a sampling sponge of FIG. 1.1; and,

FIG. 1.8 is a perspective view of the handle for holding a sampling sponge of FIG. 1.1 but shown in an alternate position.
The broken lines depict environment that forms no part of the claimed design.
